CLAIM

The ornamental design for a monitoring camera, as shown and described.

DESCRIPTION

FIG. 1 is a bottom, front, right side perspective view of a monitoring camera showing our new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a bottom plan view thereof; and,

FIG. 7 is a top plan view thereof.

The broken lines in the drawings are for the purpose of illustrating portions of a monitoring camera that form no part of the claimed design.

1 Claim, 7 Drawing Sheets
